(No Model.)

O. SMITH.

FEED REGULATOR FOR ROLLER MILLS.

No. 372,939.

Patented Nov. 8, 1887.

UNITED STATES PATENT OFFICE.

OSWALD SMITH, OF TELL CITY, INDIANA, ASSIGNOR OF ONE-HALF TO
W. T. PYNE, OF LOUISVILLE, KENTUCKY.

FEED-REGULATOR FOR ROLLER-MILLS.

SPECIFICATION forming part of Letters Patent No. 372,939, dated November 8, 1887.

Application filed August 4, 1886. Serial No. 209,976. (No model.)

To all whom it may concern:

Be it known that I, OSWALD SMITH, a citizen of the United States, residing at Tell City, in the county of Perry and State of Indiana, have invented certain new and useful Improvements in Feed-Regulators for Roller-Mills; and I do hereby declare the following to be a full, clear, and exact description of the invention, such as will enable others skilled in the art to

10 to which it appertains to make and use the same.

This invention relates to that class of devices which are used for feeding grain, &c., to roller-mills and middlings to purifiers. Grain of all kinds, middlings, &c., when poured from a spout 15 upon any surface spreads out at the base and piles up in a conical form, the sides of the cone assuming a slant peculiar to the material, somewhat influenced by the dampness or dryness of the atmosphere at different times. For 20 instance, when very dry and clean, wheat might spread two feet at the base of a cone whose center is only six inches high, while if it were damp and dirty it might rise to a height of nine inches or a foot at the center before spreading 25 ing two feet at the base.

To produce the best result in grinding grain, &c., it is very important that the material to be ground shall be delivered to the grinding-rollers evenly along their whole length at all 30 times, whether the material enters the hopper evenly or not.

To that end this invention consists in the construction and combination of parts forming a feed-regulator for roller-mills, hereinafter described and claimed, reference being had to the 35 accompany drawings, in which—

Figure 1 is a side elevation of a mill-feeding hopper, partly broken away to show my feed-regulator; and Fig. 2 is a plan view of the 40 same with the cover removed.

3 represents the hopper of a grinding-mill, into which hopper the material to be ground is permitted to run through any suitable spout, such as 4. The two ends 5 5 of my 45 hopper are vertical and the side 6 is at a fixed slant. The side 7 of the hopper is hinged to the ends 5 at 8, upon arms 9, so as to rise and fall at its lower edge as a gate, while its upper portion moves forward and backward, serving 50 as a pressure-board. This piece 7, serving in

the capacities of a gate, a pressure-board, and a side of the hopper, will, for the purposes of this specification, be called by either one of the said names most appropriate to the associations.

55

10 is a feeding-roller journaled in the frame of the hopper and serving as a bottom to the latter. It is revolved continually, as usual, in the direction of the arrow by means of a pulley, 11, and belt 12, to carry grain out of the hopper beneath the gate 7 and discharge or feed it upon the grinding-rollers, which are located, as usual, below the feed-roller and hopper, and not here shown.

60

13 is a side of the box portion of the hopper, 65 and has no other duty than to cover in the works.

14 is a bell-crank lever pivoted in the upper part of the hopper, one of its arms being connected with the upper edge of the board 7 by 70 a wire, 15, and its other arm being provided with a weight, 16, and a set-screw, whereby the weight may be fixed at any point on the arm to adjust it to the work required.

17 represents flexible connections—such as 75 cloth—secured at one edge of each of the inner faces of the pressure board, thence extending across the joints between the pressure-board and the ends 5, and secured at the other edge to the respective ends 5 of the hopper on 80 lines located on the said ends between the pressure-board and the opposite side, 6, of the hopper, the back of the cloth resting against the end of the hopper. These connections 17 are to prevent any grain from entering or passing 85 through the joints between the pressure-board and hopper ends. If the grain were to pass through the joint, it would accumulate behind the board and stop its action. If the grain enters that joint at all, it wedges between 90 the board and hopper end, impeding at first and finally stopping the action of the board. I make the pressure-board to serve as one full side of the hopper to get the greatest possible surface for the grain to act upon in its fluctuations, thus insuring sensitiveness of action. I make the joints between the board and hopper ends as close as possible, and leave the 95 board free to swing, in order that the weight of the grain may not press the cloth 17 into the 100

joints and interfere with the action of the board. When the board is heaviest loaded, it is pressed farthest back or outward relatively to the hopper, and the cloths are nearest straight, resting almost flatly against the hopper ends 5. As the grain recedes and the load grows lighter, the board moves inward, and the cloths being thereby slackened necessarily form into wrinkles. These wrinkles cannot be 10 accommodated with space outward or back of the cloth, because the latter rests as closely as possible on the board and hopper ends, so the wrinkles are forced to form inward. Thus the cloth wrinkles move inward when the board 15 moves inward, and they straighten or move outward when the board moves outward, thus acting in conjunction with the pressure-board toward the desired result.

Heretofore in those feeders which are 20 controlled by pressure-boards provided with flexible connections similar to my cloths 17 the cloths were in each instance nearly equal in area to the pressure-board, and so placed as to receive and support the same amount of 25 pressure per square inch from the grain as the pressure-board itself. Those cloths are so placed that when grain accumulates on their front and the board yields thereto the cloths do not yield in like manner to the same amount, 30 but they bag backward, and when the board should again start freely forward the loaded cloths hang upon it and impede it. Whether the board be moving forward or backward, the load on the cloths impedes its freedom of action 35 and causes the action to be spasmodic. In such devices the cloth has heretofore been a positive element acted upon by the weight of the grain. In this respect my cloths differ in their action from all others. Being sup- 40 ported at their backs, they have no pulling action on the board and do not impede it in any way. They do not support any part of the pressure of the grain, but they allow the grain to rest upon the board the same as though 45 there were no cloths, and yet the cloths are there to prevent the passage of grain into the joint, and they have no other office, and do not produce nor interfere with the production of any other effect.

50 The hinge-pins 8 are fixed in bell-crank levers 18, which are pivoted at 19 to the ends 5 of the hopper, and are provided with handles 20, whereby they may be forced to move against the resistance of the gate 7, which is hung thereon, and are further provided with slotted arcs and set-screws 21, whereby the pivots 8 may be raised or lowered and be fixed at will. By these adjustable hinges two objects are accomplished: First, the wear of the edge 55 of the gate and the feed-roller may be compensated for; second, the gate may be so set that while swinging through the extent of its arc of motion it will barely reach to the roller, or so that it will reach within one-sixteenth of 60 an inch thereof, or to any other distance, as desired. To act in conjunction with these 65 hinges, made adjustable in a direction nearly

parallel with the motion of the gate, I have provided a cam or latch, 22, in the path of the weighted arm of the bell-crank lever 14. When 70 the mill is not in operation, the said arm should be pressed down to forcibly close the gate, so that material will not escape from the hopper and accumulate on the grinding rollers, and the cam 22 should be set to block the arm and 75 lock the gate closed.

The operation is as follows: The miller first 80 gages the spout 4, by any usual means, to deliver grain into the hopper at the proper speed—that is, at the number of bushels per hour which the mill can thoroughly grind. He then permits enough grain to enter the hopper to spread to its ends and starts the mill, watching carefully for awhile to see if the head of grain in the hopper increases or 85 diminishes. If it increases, the increased amount of grain forces the pressure-board back and increases the gate-opening, thus allowing more rapid escape of the grain and lowering its head in the hopper. If this is not the result, the weight 16 bears too heavily and must be moved inward on its arm. On the contrary, if the head of grain lowers so rapidly that the ends of the roller are likely to be left bare, the weight 16 must be set farther out on 90 its arm to assist in closing the gate.

When this feed-regulator has thus been 95 properly adjusted to a certain kind of grain, it will deliver the grain from the roller in an even sheet from end to end, and it may require no further adjustment for a week. I attribute the ease and freedom of action of 100 this pressure-board to the described construction, which presents a large surface to be acted upon by the fluctuations in the head of grain 105 in the hopper, which also prevents the action of the board being clogged, which supports at their back the cloth-connections between the board and hopper ends, and which forces the wrinkling of the cloth to act in harmony with 110 the board. The pressure board or gate being hinged at some distance from its plane and about opposite to its edge, the pressure backward of the upper portion thereof causes the 115 lower edge to move vertically from the roller, and the action is positive, without any intermediate parts to get out of order. By this 120 construction all wearing parts except the weighted arm are protected within the hopper-box out of the way. The weighted arm is placed outside of the box, so that it may be 125 readily seen and adjusted. A pressure-board having flexible connections located to the rear of the pressure-board is not new, and I do not claim such a pressure-board nor flexible connections so located as my invention.

What I claim as my invention, and desire 130 to secure by Letters Patent, is—

1. The combination, in a hopper, of the hinged pressure-board 7, forming one side thereof, and the flexible connections 17, each connection being secured at one edge to the

face of the pressure-board and at its other edge to the hopper forward of the said board and resting against an end of the hopper, substantially as shown and described.

5 2. The combination, in a hopper, of the vertical ends 5, the pressure-board 7, hinged thereto, and flexible connections 17—such as cloth—connecting the face of the pressure-board with the ends of the hopper and resting 10 against the said ends, substantially as shown and described.

15 3. The combination, in a hopper, of the fixed ends 5, the roller 10, the pressure-board 7, the arms 9, secured near the lower edge thereof, the bell-crank levers 18, provided with handles 20, and pivoted at 19 to the ends 5 of the hopper, and slotted and provided with set-screws 21, and the hinge-pins 8, connecting the arms 9 with the arms 18, substantially as 20 shown and described.

4. The combination, in a hopper, of the pressure-board 7, provided with hinges 8 at its lower edge, the arms 9, projecting from the plane of the pressure-board, the bell-crank

lever 14, pivoted in the upper part of the 25 hopper, the connection 15 between the upper portion of the pressure-board and one arm of the bell-crank lever, and the weight 16, adjustable along the other arm of the said lever and provided with a set-screw, substantially 30 as shown and described.

5. The combination, in a hopper, of the hinged pressure board and gate 7, the bell-crank lever 14, journaled in the hopper, and having one arm within the hopper connected 35 with the said pressure board and gate, and having another arm exterior to the hopper, and a cam or latch, 22, hung in the path of the said exterior arm, substantially as shown and described, whereby the exterior arm may 40 be blocked to lock the gate closed, for the purpose specified.

In testimony whereof I affix my signature in presence of two witnesses.

OSWALD SMITH.
